PLATE LOCKING DEVICE FOR STORAGE BATTERIES

Henry H. Haupt, St. Paul, Minn., assignor to
Vesta Consolidated Incorporated, St. Paul,
Minn., a corporation of Delaware

Application June 6, 1934, Serial No. 729,222

1 Claim. (Cl. 136—81)

It is the object of this invention to provide improved means for locking the plates of a storage battery in proper spaced relation to each other while guarding against the short circuiting of the 5 plates due to accumulations of sediment on the locking device.

The invention will be best understood by reference to the accompanying drawing in which,

Figure 1 is an end view of a unit comprising the 10 positive and negative plates and separators with my improved locking device thereon;

Fig. 2 is a side elevation of the unit;

Fig. 3 is an isometric view showing one of the 15 locking strips separate from the plates;

Fig. 4 is a fragmentary, horizontal section taken on the line 4—4 of Fig. 2;

Fig. 5 is a fragmentary, vertical section taken on the line 5—5 of Fig. 1, and

Fig. 6 is an end view showing an alternate form 20 of locking strip.

My device is shown in connection with a storage battery unit comprising a group of negative plates 6 having upwardly projecting lugs 7 connected together by a cross bar 8 to which a binding post 9 is secured. Positive plates 10 are similarly connected together by lugs and a cross bar 11, a suitable binding post 12 being secured to the bar 11. Separators 13 are interposed in the usual manner between the positive and negative plates.

Extending across each end of the group of plates is a pair of locking strips 14, each formed with notches in its upper and lower edges respectively to receive lugs formed on the several plates. Each of the negative plates 6 has at one edge a lug 15 35 to engage the lower edge of one of the strips 14 and a second lug 16 to engage the upper edge of the other strip 14. At the opposite edge of each of the plates 6 there is a lug 17 engaging the upper strip 14 and a lug 18 engaging the lower strip 14. Each positive plate has at the left of 40 the unit as seen in Fig. 2, a lug 19 for engaging the upper edge of the upper strip 14 and a lug 20 for engaging the lower edge of the lower strip 14. Lugs 21 and 22 are formed on each of the positive 45 plates to engage respectively the lower edge of the upper strip 14 and upper edge of the lower strip 14 at the right of the unit as seen in Fig. 2.

As shown in detail in Fig. 3, the lower left strip 14 has a series of notches 23 in its upper edge to 50 receive and interlock with the lugs 16 and notches 24 in its lower edge to receive the lugs 20. The other locking strips have similar notches to retain the plates in proper spaced relation by engagement with the several lugs 15, 19, 17, 21, 22 and 18.

The upper edges 25 of the several strips 14 are beveled so that their upper surfaces extend obliquely at an acute angle down and away from the plates for the purpose of preventing the accumulation of sediment on the strips at such a point

as to cause a short circuit between the adjacent positive and negative plates.

In the alternate form of strips 14a, shown in Fig. 6, both the upper and lower edges 25a are beveled or inclined so that all of the strips are 5 identical and they may be inverted when necessary. For example, the notches 24a may be placed at the upper edge of a strip where it is to be used at the upper left and lower right corners of the unit (Fig. 2), while the notches 23a are placed 10 uppermost at the upper right and lower left corners on the unit, as seen in Fig. 2.

It will be evident that each of the strips 14 interlocks at one edge with lugs formed on the positive plates and at its other edge with lugs 15 formed on the negative plates so that the lugs are as widely spaced as possible and each plate is rigidly held against movement. I prefer to construct the strips 14 or 14a from material such as pyroxylin or rubber composition. When constructed from such materials the strips may be inserted while hot to permit bending, as indicated in dotted lines in Fig. 5. When cooled the strips have sufficient rigidity to retain the plates 20 securely and prevent displacement of the strips. 25

I am aware that plate locks have been used heretofore, but those with which I am familiar are subject to the objection that sediment collects on the upper edges of the locking strips in sufficient 30 quantities to form, in some cases, a short circuit between the lugs on the plates of one polarity and the adjacent plates of opposite polarity. This cannot occur with my improved locking device because of the beveled surfaces 25 and 25a which deflect the sediment away from the plates. Such 35 slight accumulation as may occur on the beveled edge extends in such a direction that it cannot come in contact with the plates without lugs and the lugs contiguous to the beveled upper edge are 40 all of the same polarity.

Having described my invention, what I claim as new and desire to protect by Letters Patent is:

A plate lock for a storage battery having positive and negative plates disposed in a group with separators between them comprising, a locking 45 strip formed from insulating material and extending horizontally across the ends of said plates in contact with the end surfaces of said positive and negative plates, lugs formed on the plates to engage the upper and lower edges of said strip, 50 said edges being formed with notches to interlock with said lugs for retaining the plates in rigid spaced relation to each other and the entire upper surfaces of said strip between the lugs being formed to extend obliquely down and continuously 55 away from said end surfaces of the plates to guard against the accumulation of sediment on the upper edge of said strip.
